HORIZONTALLY DISCHARGING POT-TYPE BURNER

George M. Schueder, Dearborn, and Harrison P. Zimmer, Rockwood, Mich., assignors to Evans Products Company, Detroit, Mich., a corporation of Delaware

Application April 9, 1947, Serial No. 740,454

2 Claims. (Cl. 158—91)

1

The present invention relates to heating apparatus, and is more particularly directed to improved constructions of vaporizing or so-called pot type burners for use in such apparatus. Illustrative uses of the improved burners of the present invention are in connection with floor supported cabinet types of unit space heaters, floor furnaces, and the like. Certain of the improvements of the present invention are generically useful in burners of the vaporizing type, including the conventional vertically discharging types. Other features of the invention are particularly related to vaporizing burners of the type which discharge the products of combustion in a direction other than vertical, such as in a horizontal direction. By way of illustration, the improvements of the invention are disclosed herein as embodying a horizontally discharging vaporizing type burner which is well adapted for use in unit type space heaters of the type which are disclosed and claimed in the copending application, Schueder, Serial No. 35,917, filed June 29, 1948, and in the copending application of the present applicant Schueder, Krokus and Tracht, Serial No. 36,738, filed July 2, 1948, both said applications being assigned to the assignee of the present invention.

Principal objects of the present invention are to provide improved burners of the vaporizing type, which are simple in construction, economical of manufacture and assembly, and which are reliable and efficient in operation; to provide such constructions wherein the shape of the burner body is such as to substantially reduce the overall height of the burner and wherein, more particularly, the burner body is generally elbow-shaped, defining a generally horizontal burner or vaporizing floor and a burner outlet from which heated gases are discharged in a generally horizontal direction; to provide such constructions embodying an improved arrangement of primary and secondary air openings, which cooperate in an improved manner in causing the vaporized fuel to properly travel through the elbow-shaped passage and in insuring the formation of a combustible mixture of such vaporized fuel and air; to provide such constructions wherein the arrangement of the primary openings permits the location of the burner outlet at a desirably low level with respect to the burner floor; to provide such constructions embodying improved means for insulating the burner floor, so as to promote a desired rate of vaporization of the fuel; to provide such constructions embodying an improved casing or shroud for the burner body and further embodying an improved arrangement of air openings in the casing, associated with the primary and secondary air openings of the burner body; to provide such con-

2

structions embodying an elbow-shaped burner body having a generally horizontally discharging outlet at one end, a vaporizing floor at the other end, and a pilot ring positioned adjacent the burner floor; to provide an improved construction of burner or vaporizing floor which improves the vaporizing action of the burner; and to generally improve and simplify the construction and arrangement of burners of the vaporizing type.

With the above as well as other and more detailed objects in view, which appear in the following description and in the appended claims, a preferred but illustrative embodiment of the invention is shown in the accompanying drawings throughout the several views of which corresponding reference characters are used to designate corresponding parts and in which:

Figure 1 is a perspective view of the improved burner of the present invention, embodied in a cabinet type space heater of the type specifically disclosed and claimed in the aforesaid copending application Serial No. 35,917;

Figure 2 is a top plan view of the burner of Figure 1;

Figure 3 is a view, generally in vertical central section, taken along the line 3—3 of Figure 1;

Figure 4 is a view in front elevation, taken along the line 4—4 of Figure 3;

Figure 5 is a fragmentary sectional view taken on the line 5—5 of Figure 3;

Figure 6 is a fragmentary sectional view taken along the line 6—6 of Figure 3;

Figure 6A is a view, generally like Figure 6, but showing a modification of the invention; and,

Figure 7 is a fragmentary view, based on Figure 3, of a modification of the invention.

It will be appreciated from a complete understanding of the present invention that, in a generic sense, the improvements thereof may be embodied in vaporizing burners of various different specific constructions, adapted for any of a variety of different specific applications, cabinet type space heaters and floor furnaces having been mentioned heretofore as illustrative of such uses. Certain features of the invention are peculiarly related to the non-vertically (and preferably horizontally) discharging types of burners and other features have a more generic application.

Referring now to the drawings, the illustrated improved burner, designated as a whole as 10, comprises generally a protective shroud or casing 12, and an elbow-shaped burner body 14 which is disposed within the casing 12, and is protected thereby from undesirable air currents which might adversely affect the introduction of air

to the burner body through the hereinafter described primary and secondary air openings.

Generally stated, the burner body 14 is elbow-shaped, having a closed lower end 16 which constitutes a generally horizontally disposed vaporizing floor, and a generally vertically disposed outlet, defined by relatively closely spaced burner and secondary rings 18 and 20.

The term elbow shaped is used herein in a generic sense as comprehending any configuration which causes gases issuing (in this case, rising) from the vaporizing floor 16 to follow a path having a substantial bend therein so that the gases emerge from the burner outlet in a non-vertical direction.

Fuel is supplied to the burner floor 16, through an inlet opening 22, which communicates, through a usual float controlled and regulatable supply valve 24, with a source of supply of fuel (not shown). To accommodate low fire or pilot operating conditions, means are provided to protect the pilot flame, and this means may conveniently comprise a pilot ring 26, which is positioned at a slight angle to facilitate bending of the gases as mentioned hereinafter and is located a relatively short distance above the burner floor.

In the region between the burner floor 16 and the secondary ring 20, the burner body 14 is provided with a plurality of rows of primary air openings 28, 30, 32, 34, 36, and 38, the number and distribution of which constitute an important phase of the present invention and are described in more detail below. In the region between the burner ring 18 and the secondary ring 20, the body 14 is provided with a plurality of rows of secondary air openings 41, 43 and 45, the number and distribution of which are also discussed in more detail below. Air for combustion purposes enters the body through the primary and secondary openings, and is admitted to the interior of the casing, through an enlarged opening 40 in the rear wall of the shroud and through two series of openings 42 in the side walls of the shroud.

Before considering the above identified generally described elements in more detail, it is noted that the burner 10 is removably associated with a generally L-shaped expansion drum 44, composed of two generally complementary sections 46 and 48. The notched out portion of the drum 44, which receives the burner 10, is closed by a horizontal partition 50, and a vertical partition 52. The interior of the drum 44 is divided into two generally parallel vertically spaced retrovertly arranged gas passages, by a baffle 54, which extends throughout the full width of the drum 44, and further extends from the partition 52, to a point within a relatively short distance of the left-hand end of the drum 44. As is discussed in more detail below, depending upon the setting of the control valve 24, combustion takes place either within the body of the burner 10, or within the lower pass of the drum 44, immediately adjacent the burner outlet. Heated gases, resulting from the combustion process, pass through the lower pass of the drum, around the end of the baffle 54, into the upper pass of the drum, and are discharged to the stack, through the stack connection 56. The portion of the drum 44 immediately above the burner 10 constitutes a draft regulator chamber, into which air for draft regulating purposes is admitted through the connection 58.

The above expansion drum has the funda-

mental advantage that the under side of the lower pass of the drum constitutes a primary heat transfer surface, and the present horizontally discharging burner 10 has the important advantage of a low overall height, which permits such under surface of the drum to be located comparatively near the bottom of the enclosing cabinet 60. Reference is made to the aforesaid copending application, Serial No. 35,917 for further description of the drum, cabinet, and arrangements whereby heat is extracted from the heating transfer surfaces of the drum and delivered to the surrounding surface.

Referring now to the details of the construction of the burner 10, the substantially elbow-shaped body 14 is illustrated as being conveniently formed of three interconnected substantially cylindrical sheet metal sections 62, 64, and 66, each of which is truncated to provide the elbow shape. The individual sections are secured together in end to end relation in any suitable manner, as by a weld extending continuously around the joint therebetween, all as is described in more detail in the aforementioned copending application of Schueder, Krokus and Tracht, Serial No. 36,738, filed July 2, 1948.

The lower end of section 66 is closed by the previously identified vaporizing or burner floor 16, which is circular, and which, in accordance with an important feature of the present invention, is slightly domed as indicated at 16a. As shown in Figure 3, the fuel inlet 22 is positioned at the side, and at a point very close to the level of the periphery of the floor 16, whereas, in Figure 7, the inlet 22a is substantially opposite to the burner outlet 18-20.

The burner floor 16 and the adjacent wall portions of section 66 thus define an annular reservoir or storage space for liquid fuel, into which such fuel is introduced through the inlet 22, and from occupied portions of which such fuel may gradually rise, by a natural physical action which would appear to be related to capillary action, towards the higher or domed central portions 16a of the burner floor. The shape of the floor 16 (including the height of the domed center above the annular rim, and also the configuration of the floor between the center and the periphery), is of critical importance, limiting values being given below when properly proportioned, this generic arrangement of the fuel-receiving and vaporizing portions of the burner achieves several important advantages, some of which may briefly be outlined as follows.

As will be understood, the liquid fuels customarily used in heating apparatus of the present type fall within the general class of non-homogeneous hydrocarbons, the several constituents whereof have a wide range of boiling points, and which also contain a certain percentage of relatively unstable and carbonizable constituents. In vaporizing such fuels for admixture with an air stream and ultimate combustion, it is very desirable that the fuel be passed gradually through areas of progressively increasing temperatures, so that the lighter constituents can vaporize before they reach areas of high temperature. Abrupt subjecting of such constituents to high temperature regions results in objectionable deposits on the burner floor, and this difficulty is markedly minimized by the just-mentioned gradual transition.

It will be noticed that the oil flows during the course of the progressive vaporizing action, in

the same direction as does the air which is being admixed therewith, the oil being derived from the annular reservoir, and the air from the circumferentially distributed holes. This unity of direction is important from the standpoint of efficient utilization of the available vaporizing area.

Heat for vaporizing purposes is derived, in heating apparatus of the type to which the present structures relate, primarily by radiation from the flame, and consequently it has become conventional to so arrange the burner body that throughout the full range from high fire to low fire settings, the burner floor can "see" the flame, which arrangement is also employed in the structure now being described. The present arrangement is further such that the portion of the burner floor which sees the flame is the central or raised portion 16a thereof. Accordingly, in the present structure, as distinguished from prior structures wherein the center of the burner floor is depressed, oil for vaporizing purposes is stored in the materially cooler annular reservoir portion and reaches the relatively hotter central portion only after a gradual ascent along the slightly upwardly sloping floor portion between the rim and the center.

The term "materially cooler" is relative only, in comparison with the higher temperature of the central domed or convex portion, it being important that the temperature of the annular area be below values at which carbonization or cracking or coking can occur. However, the temperature of the annular area is high enough to give a large heat input to the oil in this thin or shallow, relatively wide, annular or ring form, thereby preparing the oil for completion of the vaporizing action. For a given quantity of oil in the burner, a much larger surface area of oil is thus exposed to the preparatory heating action than would be the case with a single oil receiving depression at one side of the burner.

It will further be understood that the rate at which oil flows from a reservoir toward a vaporizing area under the influence of the previously mentioned capillary or wetting action is, generally stated, a function of, among others, the length of the boundary line of the reservoir from which the spreading takes place. In the present structure, the peripheral length of the portion of the annular reservoir which is occupied by oil is, in general, a function of the rate at which oil is introduced through the inlet. The boundary of an annular reservoir is, of course, relatively long per unit area of the reservoir and consequently the annular shape of the present oil reservoir provides, throughout the range of settings of the float valve, a desirably long boundary line from which the oil may flow towards the hotter vaporizing floor areas. Thus, flow occurs from all directions toward the raised central portion.

Coming now to the question of critical values for the shape of the burner floor 16, it has been found that if the rate of rise of the area across which the oil film advances is too steep, that the rate of advance is unduly slow and that the central portion actually becomes inactive. Conversely, if the rate of rise is too low, oil accumulates to an undesirable pool-like depth over too great a portion of the floor area; i. e., the ring-like pool is too wide. Constructions which introduce both of these difficulties are illustrated in various prior patents, for example, the Behrendt Patent No. 2,302,287.

In accordance with the present invention, it has been found that the domed center should be

maintained at a height such that the average slope of the vaporizing floor does not exceed ten per cent (10%); that is, in a burner having a floor diameter of 8", the center should not rise more than approximately $\frac{3}{8}$ " above the rim. Preferably, the rise in such a burner is approximately $\frac{1}{8}$ ". It has further been found that the slope should be approximately linear, starting near the periphery. Within these limits, a floor which represents a segment of a spherical surface is satisfactory, and such a surface may vary readily be formed from sheet metal by simple die-forming operations.

The present arrangement is also a marked improvement in connection with the generally troublesome pooling problems. As will be understood, pooling, as the term is generally understood in the industry, takes place principally when changing relatively rapidly from low to high fire settings. The problem is thus more acute in automatically controlled heaters which in response to thermostatic or other apparatus, abruptly change float valve settings from full heat to pilot heat conditions. No automatic control apparatus for the float valve is illustrated herein, but it will be understood that such automatic control apparatus may be provided if desired. Even under fixed valve settings, as in manually regulated space heaters, or during the "on cycle" of an automatic heater, there appears to be a lack of true equilibrium between the rate of oil delivery and the rate of oil vaporization or the rate at which heat is supplied to the vaporizing floor. Thus, in either manual or automatic heaters, there may be a varying amount of unvaporizing oil distributed about the vaporizing floor, each change in such amount representing at least a partial transition or pooling condition. With the present structure, wherein the unvaporized fuel is stored in a relatively cooler portion of the burner body (the annular space), such transitions have little if any adverse effects, since the additional excess oil still passes gradually, and from a desirably long boundary line, from relatively low temperature regions to relatively high temperature regions.

In further accordance with the present invention, means are provided to insulate the burner floor 16, which means serves not only to prevent an undesirable loss of the just-mentioned radiated vaporizing heat, but also to protect adjacent portions of the associated heater from such heat. More particularly, in accordance with the present invention, a heat insulating shield 70 is secured to the underside of the floor 16, as by an attaching screw 72. Shield 70 has a generally planar body portion, and oppositely disposed flanges 74, which abut the under side of the floor 16, and maintain the body in spaced relation to the floor 16, thus affording a substantially dead air insulating area, particularly in the hot spot center. If desired, the ends of this dead air space may be closed, but this has not been found to be necessary. The shield 70 lies intermediate the floor 16, and the lower wall 76 of the casing 12 and a further heat insulating space is thus defined between elements 70 and 76.

The outer end of the body section 62 is flanged as indicated at 80, which flange is suitably secured, as by spot welding or otherwise, to the body of a peripherally flanged mounting panel 82. Panel 82 is provided with fittings 84 and 86, which serve to removably secure the burner 10 as a whole, to the previously identified sup-

porting partition 52. Partition 52 is provided with an opening 90 leading from the burner into the drum 44, and which opening is surrounded by a recessed seat 92 which receives the burner 10.

The previously identified burner ring 18, which may be conventionally formed of cast iron or the like, is provided with a central outlet 94, and the peripheral portion of the ring 18 is directly received by the seat 92. Such peripheral portion of ring 18 is removably secured to the panel 82, as by screws 96, and a gasket or other sealing element 98 is interposed between elements 18 and 82. It is here noted that Figure 4 is drawn with the cabinet partition 52 omitted.

The previously identified secondary ring 20 is removably secured within the body of the burner section 62, by means of a plurality of bendable clips 100, and is provided with a central aperture 102, which cooperates with aperture 94 in defining the burner outlet. To promote the low level discharge of the burner, apertures 94—102 are preferably placed at a point not higher than the horizontal axis of the section 62, and, as shown, such openings and section 62 are coaxial.

The present general organization, including the number and distribution of the primary and secondary air openings makes it possible to use the illustrated large burner outlet which as stated above, is preferably concentric with the final burner section 62, and such a large outlet, arranged as aforesaid, provides several important advantages. For example, the large outlet makes it possible for a substantial portion of the previously described burner floor to "see" the luminous flame, even at high fire settings, and thus the burner floor receives ample radiant or vaporizing heat. This arrangement further makes it possible to make use of the desirable pilot ring without objectionably reducing the area of the burner floor which sees the flame. Viewed otherwise, the present concentric arrangement is much simpler to fabricate and manufacture, the importance of which feature will be appreciated by production men in the highly competitive field to which the present invention relates.

As a specific example, the illustrated structure has a choke ratio, i. e., the ratio between the cross-sectional area of the burner body and the area of the burner outlet, of approximately 2.65 to 1. Markedly improved operating results have been found available in structures in which this ratio is up to three-to-one.

The previously identified pilot ring 26, is removably secured adjacent the upper end of the lowermost section 66, by a plurality of bendable clips 104, and is provided, as shown, with a substantially central opening 106, which is substantially concentric with the slightly ellipsoidal outer periphery of ring 26. As shown, ring 26 is disposed at a slight angle, which action promotes the "bending" of the gases as they rise from the burner floor 16. In the preferred practice of the invention, the angularity of ring 26 is such that it extends substantially normal to, or makes a maximum angle with, the gas path. Stated otherwise, the ring 26 lies substantially normal to the imaginary arcuate line which extends from the center of the floor 16, through the center of the section 64, and also through the center of the burner outlet. Further, and as illustrated, it is preferred that the pilot ring 26 lies between successive rows of primary air openings, so that all of the openings in a particular row lie on one side or the other of the pilot

ring and so that none of such rows are intersected by the pilot ring.

The relation between the inclined pilot ring 26 and the oil inlet to the vaporizing floor is also important. In Figure 3, as previously mentioned, inlet 22 is at the side whereas in Figure 7, the inlet 22a is opposite the outlet 18—20. In both arrangements, the inlet lies beneath the relatively higher one-half of the pilot ring. Thus, under substantially all operating conditions, much of the vaporized fuel rises from a portion of the burner floor which is below the upper one-half of the pilot ring 26. This arrangement causes the fuel vapors to rise naturally along a line substantially normal to the ring 26, which produces a desirably turbulent flow of such gases through the opening in the ring, and is particularly preferable to known arrangements wherein the oil inlet is beneath the lowest portion of the pilot ring. In such known structures the gases flow along the under side of the ring, which action, in addition to producing insufficient turbulence, also requires that the gas stream shall bend through a substantial angle in passing through the opening in the pilot ring. Generically, therefore, it is proposed in the present structure to utilize an inclined baffle ring and to dispose the fuel inlet below at least the higher one-half of such ring.

30 The casing 12 is composed of a generally U-shaped sheet metal section 110, which defines the side and rounded rear end wall of the casing, and generally flat top and bottom walls 112 and 76, members 110, 112, and 76 being secured together in any suitable manner, as by welding. The open left-hand end of the casing is received within the flanged body of the mounting panel 82, and may be removably secured or permanently secured therein in any desired manner. The 40 walls of casing 12 are imperforate, with the exception that the rounded rear wall is provided with a relatively smaller upper opening 120 and the previously identified relatively larger lower opening 40, and with the further exception that 45 the side walls are provided, in alignment with the space between the burner and secondary rings 18 and 20, with two series of vertically spaced secondary air inlet openings 41. As will be appreciated, the opening 120 affords access to the usual closable lighter fitting 130. Opening 40 serves primarily to admit air for combustion purposes to the previously identified primary air openings of the burner, and the openings 42 serve primarily to admit secondary air to the 50 secondary air openings 41. It will be appreciated that the casing 12 serves to protect the burner 14 against eddies, gusts, and the like which might have an adverse effect upon the flow of air through the primary and secondary air openings in the burner body.

Coming now to the number and distribution of air openings in the burner body, it is noted that these factors have been found to be of primary importance in overcoming difficulties which, so far as the present applicants are aware, have, prior to the advent of the present invention, prevented the design of successful horizontally discharging vaporizing burners.

In this specification, the term primary air refers to all air entering in advance of the initial discharge ring 20. This air includes the pilot air which, in this embodiment, enters in advance of the pilot baffle or ring 26. Generically, pilot air is considered as that air being composed of those air pencils which control the initial mixing

of air with the vapors rising from floor 16, those air pencils which sweep across or impinge upon the vaporizing floor or its layer of vapor, or those pencils which control the vapor pressure in the pilot region immediately above the vaporizing floor. Secondary air, in turn, is that air which is admitted adjacent the exit or discharge portion of the burner, in quantities sufficient to complete combustion for desired efficiency and CO₂ ratio.

In horizontal burners, it is necessary to cause the gases which rise from the vaporizing floor, to bend through an angle of approximately 90 degrees and discharge through the burner outlet. Under pilot conditions, the flame may exist immediately below or rest upon a portion of the margin of the opening 106 in the pilot ring in which event these gases are constituted by the products of combustion of the pilot flame and by air entering through the primary openings above the pilot flame.

Under high fire conditions, these gases are composed of mixtures, in varying degrees of completeness, of fuel vapors and air. At intermediate fires, these gases may consist in part of unburnt mixtures of fuel, vapor, and air and in part of products of combustion. The action of the primary air openings appears to be particularly significant at the intermediate and higher fire settings under which conditions they serve to introduce annularly compacted radially inwardly directed pencils of air into the rising column of fuel vapors, which pencils of air must both promote a complete mixing, by creating a certain amount of turbulence within the burner body, and must also serve to deflect this rising column of fuel vapors and air so as to cause it to bend along the axis of the elbow.

It has been found in accordance with the present invention, that the total area of the primary air inlet openings (taking the orifice coefficients into account), on the "outer side" of the elbow, or the "outer side" of the gas path, should be well in excess of, the total area of the primary openings on the "inside" of the elbow, or of the gas path. In the preferred practice, the ratio of areas of outer holes to inner holes is of the order of two to one. In the illustrated embodiment, this ratio is 63/30, and it has been found that a ratio of at least 3/2 is needed for best results. In the present specification, the "outside" of the elbow, or of the path, is constituted, in Figure 3, by that portion of the interior of the elbow which lies above and to the right of an imaginary surface which extends normal to the surface of the paper, and which includes the arcuate central axis *x* of the body. As an example, and as illustrated, six rows of primary air inlet openings 28, 30, 32, 34, 36, and 38 may be provided in a burner having a burner floor area of approximately 120 square inches, and otherwise scaled as shown in the drawings. These openings may all have an initial diameter of approximately .096 inch and the number of holes in the respective rows may be as scheduled below:

	Outer Holes	Inner Holes
Row 28	13	5
Row 30	13	8
Row 32	6	4
Row 34	6	4
Row 36	12	9
Row 38	13	0

Spacing between holes in each row may be

substantially uniform. Also, the holes in rows 28, 30, 32, 34, and 36 may be radially punched, whereas it is preferred to tip the openings in row 38 so that pencils of air entering therethrough are directed downwardly. Tipping may, of course, be conventionally accomplished by first punching, inserting a pin, and tilting the pin to an angle of about 25 degrees. This also somewhat enlarges the holes, for example, from an effective diameter of .096 size to about .1065.

It will be appreciated that the combined areas of the openings in row 38 should preferably be sufficient to support complete combustion at pilot settings of the burner, so as to achieve the previously described stable location of the pilot flame. In this connection, it is noted that primarily air introduced through the openings in row 38 must additionally be in sufficient volume to maintain desirably low vapor pressures adjacent the burner floor, and must, on the other hand, be sufficiently low in volume to avoid blowing out the small candle-like pilot flame. Rows 38 and 36 provide sufficient primary air for a fire setting somewhat above the pilot setting and so on, all of the primary openings having a combined area sufficient to condition or prepare the vapor, at high fire settings (i. e., that provide a thoroughly admixed rich mixture of air and vapor, which, upon encountering the secondary openings rapidly attains combustion) and results in the provision of the commercially desirable short, fat, or bushy flame.

Further and preferably, the several rows of primary air openings lie in planes, respectively, which are substantially normal to the gas path. Thus, the rising gas stream is supplied with primary air at a desirably regulated rate.

In accordance with the invention the secondary openings 41, 43, and 45 may have a combined area very substantially in excess of the combined areas of the primary openings, and these openings serve to insure that under all conditions of operation, sufficient air will be supplied the rich air-vapor mixture before it leaves the burner outlet to complete combustion thereof. In the illustrated embodiment, rows 41 and 43 each include 100 holes, and row 45 includes 50 holes, all holes being punched to an .096 diameter. Thus in the illustrated case, the initial ratio of areas of primary and secondary openings is of the order of one to three. As shown in Figs. 3 and 6, openings in rows 43 and 45 are tipped forwardly approximately 25 degrees to plane of metal, thus effectively enlarging them from effective diameters of .096 to about .1065.

It will be noted that holes 43 and 45 are on one slope of an outwardly convex bended area, while holes 41 are on the other and more gradual slope. The tipping of holes 43, 45 thus directs pencils of air therethrough in a direction which is more or less parallel to the major plane of the burner wall. The holes of row 41 give increased turbulence and mixing by the joining of converging pencils of entering air.

The preponderance of (that is, the air admitted through rows 43 and 45 totalling 150 holes or 60%) the secondary air pencils are directed forwardly as described above to promote a rolling or swirling of the entering secondary air in the annular space between rings 18 and 20 thus more efficiently mixing this secondary air with the air-vapor mixture entering this annular space. By joining the pencils of air admitted through openings 41, with those admitted through holes 43 and 45, the aforesaid increased turbulence is achieved. The air-vapor mixture entering this

annular space is of considerably smaller volume than the air entering through rows 41, 43, and 45 and is entrained in the swirling air in this annular space.

In the modified embodiment shown in Figure 6A, the openings 41', 43', and 45' are formed in a cylindrical portion of the body section 62, the number and sizes of the holes, as well as the tipped relation thereof, being preferably as described in connection with holes 41, 43, and 45. It will be noted in comparing the two forms of Figure 6 and Figure 6A, that while the non-ribbed form of Figure 6A is simpler to manufacture, the ribbed form of Figure 6 simplifies a problem of causing convergence of the air pencils immediately adjacent the annular surface of the body. In both forms, however, convergence occurs inside of the annular space between the rings 18 and 20, which space constitutes an air mixing chamber. In the preferred and illustrated practice of the invention this premixing chamber is a space defined by a pair of rings having approximately the same outside and inside diameter, thus giving a mixing or final air chamber of substantial radial depth in contrast with, for example, structures of the type shown in Hayter Patent No. 2,415,098.

In connection with the secondary air, not only the quantity or right amount is important but its directional characteristics are of prime importance in achieving complete mixing close to the burner discharge to thus get a short or bushy flame for higher overall efficiency of the whole heater.

Although only a single specific embodiment of the invention has been described in detail, it will be appreciated that various modifications in the form, number, and arrangement of the parts may be made without departing from the spirit and scope of the invention.

What is claimed is:

1. In a burner of the vaporizing surface type, the combination of an elbow-shaped burner positioned so that one leg thereof is vertical and the other leg is horizontal and above the vertical leg, the end of the burner in the horizontal leg having a burner discharge opening transverse to the axis of the horizontal leg, the center of said opening being substantially at the axis of said horizontal leg, said vertical leg having a bottom providing a centrally located vaporizing surface and a fuel receiving and pool holding portion surrounding the surface, a dished baffle ring mounted in said burner adjacent the top of the vertical leg thereof and on an angle to the vertical so that the portion of the baffle on the inside of the elbow is lower than the portion of the baffle on the outside of the elbow, the concave portion of said baffle facing the bottom of the vertical leg, said burner having a fuel inlet opening in the side thereof adjacent said pool holding portion and located at least as far as the axis of the burner from the inside of the elbow whereby it is substantially beneath the higher half of the baffle, said burner having primary air inlet openings spaced around the periphery and along the length thereof, the total area of the primary air inlet openings on the outer side of the elbow being substantially greater than the total area of the openings on the inside of the elbow whereby more air may be admitted from the outside of the elbow bend to assist in bending the vaporized fuel around the elbow.

2. In a burner of the vaporizing surface type, 75

the combination of a shroud having an imperforate bottom, an elbow-shaped burner encased in said shroud and positioned so that one leg thereof is vertical and the other leg is horizontal and above the vertical leg, the end of the burner in the horizontal leg having an opening transverse to the axis of the horizontal leg and providing a discharge opening for the burner, the center of said discharge opening being substantially at the axis of said horizontal leg, said burner having secondary air inlets located around its periphery adjacent said discharge opening whereby a flame may be located at said discharge opening, said vertical leg having an imperforate dome-shaped floor at the bottom thereof, said floor comprising an outer annular fuel receiving and pool holding portion and a central vaporizing surface portion elevated above said outer annular portion and the level of a normal fuel pool held in said outer portion, a dished annular pilot baffle mounted in the burner adjacent the top of the vertical leg and on an angle to the vertical so that the portion of the baffle on the inside of the elbow is lower than the portion of the baffle on the outside of the elbow, the concave portion of said baffle facing said floor, the central opening of said annular pilot baffle and said central vaporizing surface being located so that at least a portion of said central surface can see a flame at said discharge opening, said pilot baffle being located so that it prevents a substantial portion of said annular fuel pool holding portion from radiation from a flame at said discharge opening, said burner being located in said shroud so that the imperforate floor thereof is spaced slightly above the imperforate bottom of said shroud, means between the imperforate floor and bottom providing an insulative barrier between them, the sides of said shroud having inlet openings for air, said burner having primary air inlet openings spaced around the periphery and along the length thereof, the total area of the primary air inlet openings on the outer side of the elbow being substantially greater than the total area of the openings on the inside of the elbow whereby more air may be admitted from the outside of the burner to assist in bending the vaporized fuel around the elbow, said burner having a fuel inlet opening in the side thereof adjacent said pool holding portion and located at least as far as the axis of the burner from the inside of the elbow whereby it is substantially beneath the higher half of the baffle.
